US00D486573S

(12) **United States Design Patent** (10) Patent No.: **US D486,573 S**
Callaghan et al. (45) Date of Patent: ** Feb. 10, 2004

(54) **HAND HELD ORAL IRRIGATOR**

(75) Inventors: **Roberta L. Callaghan**, Fort Collins, CO (US); **Charles Y. Choi**, Chicago, IL (US); **Clifford J. Snyder**, Fort Collins, CO (US); **Gary L. Sokol**, Longmont, CO (US); **Kieron H. Tse**, Chicago, IL (US)

(73) Assignee: **Water Pik, Inc.**, Fort Collins, CO (US)

(**) Term: **14 Years**

(21) Appl. No.: **29/173,526**

(22) Filed: **Dec. 31, 2002**

(51) LOC (7) Cl. **24-02**

(52) U.S. Cl. **D24/111; D24/176**

(58) Field of Search D24/111, 108, D24/176; 433/80, 81; 601/162, 165

(57) **CLAIM**

The ornamental design for a hand held oral irrigator, as shown and described.

DESCRIPTION

FIG. 1 is a left-side perspective view of a hand held oral irrigator showing our new design;

FIG. 2 is a front elevation view thereof;

FIG. 3 is a left elevation view thereof;

FIG. 4 is a right elevation view thereof;

FIG. 5 is a rear elevation view thereof;

FIG. 6 is a top plan view thereof; and,

FIG. 7 is a bottom plan view thereof.
